UNITED STATES PATENT OFFICE.

WILLIAM J. GAGNON, OF BRIDGEPORT, CONNECTICUT, ASSIGNOR TO THE BEAD CHAIN MANUFACTURING COMPANY, OF BRIDGEPORT, CONNECTICUT, A CORPORATION OF CONNECTICUT.

PLUMBING PLUG POST.

Application filed March 18, 1927. Serial No. 176,423.

My invention relates to posts for basin and sink stoppers, or the like, and more particularly to hollow plug posts suitable for attaching a ring to the stopper.

5 One object of the invention is the provision of a simple, strong, one-piece, hollow post adapted for attachment to a plumbing plug thus forming a complete stopper. Another object is the provision of a one-piece post 10 which shall be water-tight. Still a further object is the provision of a plug which can be inexpensively manufactured with the minimum of material. Other objects will be apparent upon consideration of this specification.

15 The present invention comprises a unitary hollow post, formed from a flat blank, and having certain projections and holes calculated especially to adapt the post for connection with the plug and with a ring for lifting the stopper. A post of this character is shown by way of illustration in the accompanying drawings, in which—

Figure 1 is an elevation of the hollow post 25 showing its closing seam;

Fig. 2 is a bottom view of the post shown in Figure 1;

Fig. 3 is a top view of the post shown in Figure 1;

30 Fig. 4 is another elevation of the post shown in Figure 1 taken at right angles to the previous elevation;

Fig. 5 is a vertical section of the post taken on the line 5—5 of Figure 1;

35 Fig. 6 is an assembled elevation of the entire stopper, the plug being shown in section;

Fig. 7 is a vertical section through a modified form of post;

Fig. 8 is an elevation of a modified form 40 of post constructed in accordance with the invention; and

Fig. 9 is an elevation of the stopper assembly, the plug being shown in section, and the post being of the form illustrated in 45 Fig. 8.

In the past it has been customary to manufacture posts for washbasin stoppers in solid form with appropriate flanges shaped upon them and a hole bored near the top for attaching the usual ring. Such posts, it is believed, have been unnecessarily heavy and have required an excessive amount of metal for their construction.

It has also been proposed to make plug

posts of hollow parts, but auxiliary parts 55 have been required in all cases because of the difficulty of making the hollow plug watertight. Such constructions are expensive and easy to get out of order.

According to the present invention a one-piece, hollow plumbing plug post is made water-tight without association therewith of any additional elements, and at the same time the necessary flanges are formed on the post.

60 In the drawings a unitary plumbing plug post 10 is shown. This post is formed from a single blank and is closed along a single seam 11. It has been found that the seam 11 can be closed so as to be water-tight. Thus 70 the post has a water-tight closure.

Two holes 12 and 13 are oppositely positioned near the top of the plug for the accommodation of the usual ring 14.

75 An annular flange 15 is shaped on or unitarily formed around the post a little distance below the holes 12 and 13 for a purpose which will later appear. In the embodiment shown in Figs. 8 and 9 this flange takes the form of a shoulder 15^a, the top of the post rising directly from the flange edge without immediate reduction of diameter. A second annular flange 16 is similarly shaped on the post a distance below the flange 15 equal to the thickness of the plug at its center. The 85 flange 16 is given a greater offset from the post than the flange 15 for a purpose which will be pointed out later.

It has been found advantageous to close the bottom of the post by extending the 90 metal downwardly in conical form from the circumference of the lower flange 16 to a point 17. That is to say, the closed lower end is formed on the lower flange. This conformation gives an exceedingly tight joint. 95 It is possible, however, to make the bottom closure of other than conical shape, for instance it may be flat as illustrated in Fig. 7.

In assembling this post 10 and plug 18 the post is inserted into the plug through a central hole 19 therein provided for the purpose. The post is inserted from the under side of the plug, the upper flange 15 being forced through the hole 19 in the plug and coming out on the upper side of the plug. Although 100 this is accomplished most easily where the embodiment illustrated in Figs. 8 and 9 is 105 employed, no difficulty is experienced with

the other constructions. When the post is in place the ring 14 may be inserted through the holes 12 and 13, thus completing the assembly of the stopper.

5. A stopper is usually held in place by the weight of the water above it, and sometimes it is wedged in by the person pushing on it. The stopper is always removed, however, by a pull exerted upon the ring 14. This pull 10 must be of sufficient force to remove the stopper from the position into which it is wedged, and against the weight of the water above the stopper. The flange 16 is therefore made larger than the flange 15 so as to 15 distribute this pull over a large area on the under side of the plug, and prevent the post being pulled out of the plug.

From what has already been said it will be realized that any water which may get 20 by the ring 14 through the holes 12 and 13 into the post cannot escape from the basin because of the water-tight lower end of the post. No water can escape from the basin around the post for the plug material forming 25 the hole 19 surrounds the post and fits snugly between the flanges 15 and 16 thus preventing leakage past the outside of the post.

It might be mentioned that the construction 30 illustrated in Figs. 8 and 9 is in some respects preferable to those shown in the other figures. It is more simple to manufacture, and when assembled gives the stopper a neater appearance.

35. In addition to the advantages of constructions according to the present invention which have already been enumerated there may be mentioned lightness, ease of handling, and economy in shipping to distant 40 points.

The form of post illustrated and described and the stopper construction shown in the drawings are not to be taken as limiting the scope of the invention. It is also to be noted

that where the term "upper flange" appears 45 in the claims a shoulder such as 15^a is included as well as the annular projection 15.

I claim:

1. A hollow plumbing plug post formed of a single piece of material and having 50 a water-tight closure integral therewith.

2. In an integral hollow plumbing plug post, a lower end of the post closed solely by the material forming the post, said end being 55 water-tight.

3. In an integral hollow plumbing plug post, a closed lower end forming a flange upon said post, said end being water-tight.

4. An integral hollow plumbing plug post having a hole adapted to receive a ring at 60 its top, an upper flange formed around said post below the hole, and a lower flange formed around said post, larger than said upper flange, in combination with a closed water-tight lower end formed on said lower 65 flange, substantially as described.

5. An integral hollow plumbing plug post having holes adapted to receive a ring at its top, an upper flange formed around said post below the holes, and a lower flange 70 formed around said post larger than said upper flange, in combination with a conical closed water-tight lower end formed on said lower flange, substantially as described.

6. An integral hollow plumbing plug post having holes adapted to receive a ring at its top, an upper flange formed around said post below the holes, the top of the post rising 75 directly from the flange edge without immediate reduction of diameter, and a lower 80 flange formed around said post larger than said upper flange, in combination with a closed water-tight lower end formed on said lower flange, substantially as described.

In testimony whereof I have signed my 85 name to this specification.

WILLIAM J. GAGNON.
